UNITED STATES PATENT OFFICE.

ARTHUR JAMES MASKREY, OF CHESTER, WEST VIRGINIA.

CATCHER FOR METAL PLATES.

No. 889,629.

Specification of Letters Patent. Patented June 2, 1908.

Application filed November 4, 1907. Serial No. 400,449.

To all whom it may concern:

Be it known that I, ARTHUR JAMES MASKREY, a citizen of the United States of America, and resident of Chester, county of Hancock, 5 and State of West Virginia, have invented certain new and useful Improvements in Catchers for Metal Plates, of which the following is a specification.

This invention relates to improvements in 10 catchers for metal plates, and more particularly to a new and useful tin and terne plate catcher and deliverer, and still more particularly to a machine for grasping sheets of metal as they rise from the rolls of a tinning pot and for delivering said sheets to guides 15 leading to a branner.

The primary object of the invention is to provide a mechanical catcher of the character above referred to, which is adapted for 20 use in connection with any style of tin or terne plate coating machine, and which will grasp sheets as they rise from the tinning pot and will carry the same upward and over to guides leading to the branner without injuring 25 said sheets.

A further object of the invention is to provide a mechanical device for catching metal sheets which is adjustable to meet the requirements of different sized sheets and 30 which is also adjustable to regulate the grip or pressure applied to the sheets, and which is further self-regulating, thus allowing for the gripping of plates of different thicknesses. And a still further object is to provide a 35 catcher which grips the sheets lightly along the edges thereof and which will not leave large grease spots thereon.

With these and other objects in view, all 40 of which will hereinafter be made apparent, the invention finally consists in the particular construction, arrangement and combination of parts which will hereinafter be fully described, reference being herein had to the accompanying drawings, forming a part of 45 this specification, in which—

Figure 1 is a top plan view of the invention, the same being shown mounted in place over a jumbo tinning pot; Fig. 2 is an end elevation of the same; Fig. 3 is an enlarged 50 side elevation of a pair of oppositely-disposed disks, one of which is shown partly in section; Fig. 4 is a cross-section of a disk with the teeth removed; Fig. 5 is a side elevation of a detached tooth; Fig. 6 is a top

plan view of the same; Fig. 7 is a side elevation of the guide-arms; Fig. 8 is an end elevation of a portion of the housing illustrating the vertical and horizontal shaft-adjusting means; and—Fig. 9 is a horizontal section of the same.

Referring to said drawings, in which like designating characters distinguish like parts throughout the several views—1 indicates the ordinary tinning pot, on the opposite ends of which is secured in any suitable manner, preferably by bolts 2, a small housing 3 provided at opposite sides thereof with rectangular openings 4, in which is mounted, as is clearly shown in Figs. 1, 2, 8 and 9, bearing-blocks 5. Journaled in said bearing-blocks are the opposite ends of two parallel shafts 6 and 7 on each of which are mounted a plurality of circular disks 8, the disks on said shaft being arranged in oppositely-disposed pairs. Each of said disks has a boss 9 through which an adjusting-screw 10 is projected into impinging relation with the shaft for holding said disk in adjusted position. Each disk is provided with a circular annular channel 11 therein, and in said channel is a 80 plurality of radially-disposed sockets 12 in each of which is seated a spiral spring 13, the outer end of which abuts against the flat under face 14 of a tooth 15 which is mounted, substantially as shown, upon a pivot 16. 85 Each of said teeth consists of a body portion 17 the front face 18 of which is inclined substantially as shown in relation to its said face 14, and terminates in a rounded point 19 adapted for engaging the metal plate, and a 90 rearwardly and inwardly extending lug or tail-piece 20 whereby the tooth is prevented from swinging around on its pivot 16, the bearing 21 for said pivot being located intermediate said body and tail-piece, as shown. 95

Pivoted on the shaft 6 is a guide-arm 22, clearly shown in Fig. 7, and on the opposite shaft 7 is pivoted a guide-arm 23, the lower ends or members 24 and 25 of said guides being similarly shaped and extending downward and meeting, thence spreading apart so as to straddle the point of contact of the discharge-rolls 26 of the tinning pot. The guide-arm 22 is provided above its pivotal connection with the shaft with a curved forwardly-inclined arm 27 which is adapted to incline the metal sheets forward as they rise. Said guide-arm 22 is so formed and its weight

is so distributed that it normally stands balanced upon the shaft 6 with its guide-member 24 in opposing relation to the similarly shaped member 25 of the guide-arm 23, the latter arm being provided with a balance-weight 28 which is adapted to normally hold said member 25 thrust forward, as shown.

Mounted on the edge of the pot 1 are uprights 29 supporting an inclined double chute 30, said chute being composed of a plurality of parallel bars 31, upon which the sheets of metal fall as they are passed upward by the disks. At each side of the chute is provided a side-guide 32, and intermediate 15 said guides is a central guide 33 which divides the respective ends of said chute. The upper ends of said inclined parallel bars 31 are curved and overlie the shaft 7 in position to receive a sheet passed upward between 20 the teeth of the disks. The lower end of said chute 30 is suitably mounted for directing sheets therefrom to suitable tables 34 arranged for discharging said sheets to a guide leading to the branner.

25 The bearing-blocks 5 are fitted in the rectangular openings 4 of the housing 3 so that they will have considerable play, as is clearly illustrated in Figs. 8 and 9, and a horizontally directed adjusting-screw 35 is provided 30 through the housing 3 whereby said blocks, bearing the shafts, may be adjusted with relation to each other, means being thus provided whereby the pressure of the teeth of the disks upon the sheets may be regulated.

35 Extending upward through the housing 3 into the under side of each bearing-block is an adjusting-screw 36, whereby the shafts may be raised or lowered to adapt the machine to sheets of metal of different lengths.

40 A driving shaft 37 is suitably mounted at one end of the tinning pot, said shaft having fixed thereon a drive-wheel 38 and a gear-wheel 39, the latter being in meshing engagement with a gear-wheel 40 on the shaft 6. At the opposite end of the machine, a gear-wheel 41 is mounted on the shaft 6, said gear-wheel meshing with a similar gear-wheel 42 mounted on the shaft 7.

The operation of the invention is substantially as follows: The metal sheet 43 rises between the discharge rolls 26 of the tinning pot, and, as it rises, is grasped by the opposing teeth 15 of the disks 8, which disks are geared so that their peripheral speed is the 55 same as that of the rolls 26, and is carried upward by said teeth as said disks revolve, the upper edge thereof engaging the inclined arm 27 by which it is thrown forward so that when the whole sheet has passed from between the teeth it will fall upon the bars 31 of the chute 30. Directed by the guides 32 and 33, said sheet slides forward to the tables 34.

As is apparent from the foregoing, I provide 65 an extremely simple and efficient device

for the purposes specified, and, since the bearing surface of the teeth upon the sheet is very limited in extent, the latter is but little liable to be injured or marred by contact with said teeth. The present construction overcomes the objection to a plain disk, which objection lies in the fact that such plain disks smudge the sheets with grease or palm-oil from the pot.

Having thus described my invention, what I claim as new, and desire to secure by Letters Patent, is—

1. In a catcher for metal plates, the combination with a tinning pot, of housings, two parallel shafts journaled in said housings over the discharge rolls of the tinning pot, a plurality of circular disks mounted on said shafts, yieldable sheet-grasping teeth carried by said disks, guides for directing a sheet through said disks, an inclined chute on which the sheet is actuated to fall, and means for driving said shafts.

2. In a catcher for metal plates, the combination with a tinning pot, of suitably mounted housings, two parallel shafts journaled in said housings over the discharge rolls of the tinning pot, a plurality of circular disks fixed on said shafts, said disks being arranged in oppositely-disposed pairs, spring-pressed sheet-engaging teeth carried by said disks, guides carried by said shafts, a sheet-guiding arm on one of said shafts, an inclined chute, and driving means for said shafts.

3. In a catcher for metal plates, the combination with a tinning pot, of suitably mounted housings, two parallel shafts journaled in said housings over the discharge rolls of the tinning pot, a plurality of circular disks fixed on said shafts, said disks being arranged in oppositely-disposed pairs, spring-pressed teeth carried by said disks, said teeth being arranged to normally meet as they rise above the point of contact of the discharge rolls of the tinning pot, guides for directing the sheet to said disks, an inclined chute on which the sheet is adapted to fall, and driving mechanism for said shafts.

4. In a catcher for metal plates, the combination with a tinning pot, of suitably mounted housings, two parallel shafts journaled in said housings over the discharge rolls of the tinning pot, a plurality of circular disks fixed on said shafts, said disks being arranged in oppositely-disposed pairs, pivoted teeth carried by said disks, said teeth being arranged to normally meet as they rise above the point of contact of the discharge rolls of the tinning pot, a chute to which a sheet is directed from said disks, and driving mechanism for said shafts.

5. In a catcher for metal plates, the combination with a tinning pot, of suitably mounted housings, two parallel shafts journaled in said housings, a plurality of circular disks fixed on said shafts, said disks being ar-

ranged in oppositely-disposed pairs, pivoted teeth carried by said disks, said teeth being adapted for yieldingly grasping a sheet of metal as it rises from the discharge rolls of the tinning pot, guides for directing sheets from the pot to said disks, a chute to which said sheets are delivered, and mechanism for driving said shafts.

6. In a catcher for metal plates, the combination with a tinning pot, of suitably mounted housings, two parallel shafts journaled in said housings over the discharge rolls of the tinning pot, a plurality of circular disks fixed on said shafts, said disks being arranged in oppositely-disposed pairs, pivoted teeth carried by said disks, said teeth being adapted for simultaneously engaging a sheet of metal on opposite sides thereof as it rises from the discharge rolls of the tinning pot, guides for directing the sheet to said disks, a chute to which said sheets are delivered, and mechanism for driving said shafts.

7. In a catcher for metal plates, the combination with a tinning pot, of two parallel shafts journaled over the discharge rolls of the tinning pot, a plurality of circular disks fixed on said shafts for grasping and carrying a metal plate upward from said discharge rolls, spring-pressed teeth carried by said disks, said disks being arranged in oppositely-disposed pairs with their teeth in opposing relation, and mechanism for driving said shafts.

8. In a catcher for metal plates, the combination with a tinning pot, of two parallel shafts journaled over the discharge rolls of the tinning pot, a plurality of circular disks fixed on said shafts for carrying a metal plate upward from said discharge rolls, said disks being arranged in oppositely-disposed pairs, guides for directing a sheet from said rolls to said disks, a delivery chute, and means for directing a sheet from said disks to said chute.

9. In a catcher for metal plates, the combination with a tinning pot, of parallel shafts journaled over the discharge rolls of said pot, driving means for said shafts, a plurality of circular disks carried in oppositely-disposed pairs by said shafts, pivoted teeth carried by said disks, springs for normally forcing said teeth outward, and means whereby said teeth are prevented from swinging clear of said springs.

10. In a catcher for metal plates, the combination with a tinning pot, of suitably mounted supports, parallel shafts journaled in said supports above the discharge rolls of the tinning pot, a plurality of circular disks carried in oppositely-disposed pairs by said shafts, and pivoted spring-pressed teeth carried by said disks, said teeth being adapted for simultaneously engaging a metal plate on opposite sides thereof as it rises from said discharge rolls.

11. In a catcher for metal plates, the combination with a tinning pot, of suitably mounted supports, parallel shafts journaled in said supports above the discharge rolls of the tinning pot, a plurality of circular disks carried in oppositely-disposed pairs by said shafts, pivoted spring-pressed teeth carried by said disks, said teeth arranged at intervals in said disks so that opposing teeth will simultaneously engage the metal plates on opposite sides thereof as it rises from said discharge rolls, guides leading to a branner, and means whereby said plate is directed to said guide.

12. In a catcher for metal plates, the combination with a tinning pot, of suitably mounted supports, parallel shafts journaled in said supports above the discharge rolls of said pot, a plurality of circular disks carried in oppositely-disposed pairs by said shaft, pivoted teeth carried by said disks, springs mounted in sockets provided in the edges of said disks for normally holding said teeth forced outward from the disks, means carried by said teeth whereby they are prevented from swinging clear of said springs, guides for directing the metal plate to said teeth, guides leading to a branner, and means whereby said plate is directed from said teeth to said guides.

13. In a catcher for metal plates, the combination with a tinning pot, of supports, parallel shafts journaled in said supports and overlying the discharge rolls of the tinning pot, driving means for said shafts, means for adjusting said shafts with relation to each other, a plurality of circular disks carried in oppositely-disposed pairs by said shafts, pivoted teeth carried by said disks, means for normally forcing said teeth outward, means whereby said teeth are prevented from swinging clear of the first-mentioned means, and means whereby the plate passed upward by said teeth is directed forward.

14. In a catcher for metal plates, the combination with a tinning pot, of supports, parallel shafts journaled in said supports above the discharge rolls of said pot, driving means for said shafts, means for adjusting said shafts with relation to each other, and means for adjusting the height of said shafts with relation to said discharge rolls, a plurality of circular disks carried in oppositely-disposed pairs by said shafts, pivoted teeth carried by said disks, springs for normally forcing said teeth outward, means whereby said teeth are prevented from swinging clear of said springs, and means whereby the plate passed upward by said teeth is directed forward.

15. In a catcher for metal plates, the combination with a tinning pot, of supports, parallel shafts journaled in said supports above and parallel to the discharge rolls of said pot, driving means for said shafts, a plurality of circular disks carried in oppositely-disposed

pairs by said shafts, each disk having an annular channel therein, teeth pivotally mounted in said channel, said teeth being spring-pressed, means for adjusting said shafts with relation to each other, and means for adjusting said shafts with relation to said discharge rolls.

In testimony whereof I affix my signature in presence of two subscribing witnesses.

ARTHUR JAMES MASKREY.
